UNITED STATES PATENT OFFICE.

WILLIAM H. CLAYTON, OF POPLAR BLUFF, MISSOURI, ASSIGNOR TO DALTON ADDING MACHINE COMPANY, OF ST. LOUIS, MISSOURI, A CORPORATION OF MISSOURI.

TYPE-WRITING MACHINE.

1,049,291.

Specification of Letters Patent.

Patented Dec. 31, 1912.

Application filed September 10, 1906. Serial No. 334,029.

To all whom it may concern:

Be it known that I, WILLIAM H. CLAYTON, a citizen of the United States, residing at Poplar Bluff, Butler county, Missouri, have invented a new and useful Type-Writing Machine, of which the following is a specification.

This invention relates to improvements in the construction, combination and arrangement of parts included in typewriting machines generally, and in the present embodiment of the invention it relates more specifically to that class of machines known as front strike typewriters, in which there is a platen or paper support having a ribbon movable across the front thereof, and in which the type-bars are mounted in position so that when operated they will strike against the ribbon in front of the platen, and thereby produce records on sheets of paper supported on the platen. In such an embodiment the invention includes improved mechanism controlling the platen for letter spacing under control of a novel train of mechanism whereby each key controls and operates its proper type-bar; an improvement in the construction of the type-bars, each of which carries three distinct characters disposed thereon in a row, and the middle one of which strikes the platen except when the parts are specially adjusted to permit others to strike and make impressions; an improved mechanism for supporting the type-bars and mechanism controlling the supporting mechanism operable to move the same as required to cause any desired character to strike the platen when the type-bars operate; improved tabulating mechanism for adjusting the platen for column printing; improved devices for rendering uniform the "touch" of the various keys which, necessarily from the construction of the parts, operate type-bars of different sizes and weights; and various other improved combinations and features of arrangement and construction, all of which are particularly set forth herein.

One object of the invention, therefore, is to produce a compact, strong and durable typewriter containing the combinations above and hereafter set forth, all designed to operate in harmony substantially as herein specified, and thereby produce records all of which will be visible to the operator

without manually moving any of the parts 55 after the records have been made.

It is a further object to arrange and combine the entire typewriting mechanism so as to provide a relatively large open space between the key levers and within the machine 60 below the platen, and toward the rear end of the machine in order that other mechanism may be mounted therein, a portion of which, in order to illustrate the location thereof, is shown in the drawings. 65

Another object is to produce a typewriter comprising two separate groups of type-bars one of which is supported in a pivotally mounted frame at each side of machine thereby leaving a central space of considerable width wherein other mechanism adapted for combination with this machine can operate without obstruction from the typewriter parts, and mechanism for moving said pivotally mounted frames as required 70 to produce impressions from the several types on each type-bar. The platen is moved only for lateral spacing and line spacing. 75

Another object is to produce in combination with the platen and the automatic letter spacing mechanism co-operating therewith, improved tabulating mechanism whereby the platen may be caused automatically to move laterally the width of one or more 85 column spaces, and including a device for restraining the platen so that it will not move or stop with too great speed or force, which would eventually damage some of the parts. Mechanism is also provided operable 90 to release the controlling mechanism from the platen so that the platen may be moved manually any required distance in either direction. 95

Other objects and advantages of my invention will appear from the following description, reference being made to the accompanying drawings in which—

Figure 1 is a side elevation of a typewriter constructed in accordance with the 100 principles of my invention, and also illustrates an independent bank of keys and key levers and a portion of the mechanism controlled thereby, said key levers and the mechanism controlled thereby being mounted 105 within the machine and below the platen, out of the way of the typewriting mechanism so as not to interfere with the opera-

tion thereof. Fig. 2 is a front view of the typewriter, and illustrates also the disposition of a portion of the mechanism under control of the independent bank of keys. Fig. 3 is a perspective view of an enlarged type head. Fig. 4 is a perspective view of the tabulating key device. Fig. 5 is a rear view of a portion of the machine illustrating the escapement mechanism whereby the movement of the platen is controlled. Fig. 6 is a rear elevation of the platen carriage and operating mechanism. Fig. 7 is a rear view of one of the groups of type-bars, one of the type-bars being shown in striking position. Fig. 8 is a top view of one of the groups of type-bars. Fig. 9 is an outer side elevation of one of the groups of type-bars. Fig. 10 is a perspective view illustrating one of the trains of the printing devices. Fig. 11 is a sectional view of one of the stationary supports for the type-bars, and the movable support is shown pivotally mounted thereon. Fig. 12 is a sectional view showing one of the type-bar spindles enlarged and the manner in which they are supported in the pivoted frames. Fig. 13 shows the construction, arrangement and supports of the platen and platen carriage, and also the escapement mechanism controlling the platen. Fig. 14 shows a device for controlling a pawl arranged to rotate the platen when the latter is moved laterally, as for column spacing. Fig. 15 is a plan view of the platen controlling escapement mechanism, and the devices for regulating the tension thereof, and for regulating the scope of movement of the parts. Fig. 16 is a partial sectional view taken on the line $a-a$ of Fig. 15 and showing in detail the devices for regulating the tension and scope of movement of the escapement mechanism. Fig. 17 is a rear view of the escapement wheel and controlling piece. Fig. 18 is a sectional view of the shaft forming part of the mechanism controlling the platen and shows in detail one of the adjustable bearings for this shaft. Fig. 19 is a perspective view of the escapement member which controls rotation of the shaft controlling the platen. Fig. 20 is a sectional view of a part of the platen carriage and support and shows a lever device for releasing the controlling mechanism from the platen carriage so that the platen can be moved laterally without restraint. Fig. 21 shows the tabulating stop devices. Fig. 22 shows a frame for supporting the levers acted on by the keys and controlling the type-bars. Fig. 23 illustrates the several forms of key-levers and the arrangement whereby their touch and scope of movement are made uniform. Fig. 24 is a view of one of the frames in which the key levers are pivoted. Fig. 25 is a view of a part of the ribbon feed mechanism. Fig. 26 is a perspective view of

the ribbon guiding device by which the ribbon is held adjacent to the surface of the platen, and which moves the ribbon over the printing line, as required to position the ribbon so that record will be made by any operated type, and also moves the ribbon away from the printing line to make visible any record thereon without moving the platen. Fig. 27 is a view of part of the mechanism for moving the ribbon guiding device to carry the ribbon to and away from the printing line. Fig. 28 shows a portion of the mechanism for moving the type-bar frames or supports to their upper and lower positions. Fig. 29 shows one of the levers included in this mechanism detached. Fig. 30 shows the supporting plate for the mechanism for moving the type-bar frames or supports. Fig. 31 shows some of the key levers mounted in their frames. Fig. 32 is a plan view of the typewriter key board and shows the position relative thereto of an independent set of keys. Fig. 33 is a sectional view showing the paper release devices supported by the carriage end plates.

The base 1 sustains rigidly the two side frames 2. The base extends forward a considerable distance beyond the side frames and the keys 3 are disposed in a conventional or preferred arrangement over the front part of the base. The keys 3 are the typewriter printing keys, and, through the medium of a train of mechanism leading therefrom, their operation results in operation of the type-bars to record or print. Two posts 100 or frame pieces 4 are secured to the base between the front ends of the frames 2. A plate 5 (Figs. 28, 30 and 32) is attached to the frame 2 at the left side of the machine relative to the operator, and to the right frame and to each of the posts or frame pieces 4 a plate 6 is fastened (Figs. 31 and 32). Between the plates 5 and 6 at one side of the machine a bearing block 7 is secured (Fig. 24) and a like block is secured between the plates 5 and 6 at the other side of the machine (Fig. 32). These blocks, which are duplicates, are provided with a number of slots 8 on their front sides and in each slot a key lever 9 is pivoted, each lever comprising a horizontal arm terminating in its key 3, and a vertical arm. The keys are arranged in transverse rows as usual in machines of this character, which requires that the horizontal arms of some of the key levers be longer than others. To compensate for this unequal length, so that the "touch" of all the keys will be uniform and so that equal movement of all the keys for writing purposes as required and maintained, the pivots are arranged nearer to or farther from the connecting devices, depending upon the length of the levers. For instance, the keys in the front row have longer levers than those in the remaining rows and

in writing all keys should be depressed the same distance to produce uniform records. To produce this result the longer or front row key levers are pivoted near their angle 5 as indicated at 10 (Figs. 23 and 31), the next row at 11, and the levers in the rear row are pivoted farthest from their angles as indicated at 12. In this manner the key levers are pivoted in two groups, leaving 10 between said groups a relatively large open space which may be understood by referring to Fig. 32.

At the rear of the machine two shafts 13, 14 are supported by the side frames 2. A 15 pair of arms 15 near each side of the machine are removably secured to said shafts by clamp devices 16. The forward ends of each pair of arms are connected by one or more rods 17 thereby forming a strong 20 frame, and another rod 18 is supported in each frame behind said rods 17. A number of substantially vertical levers 19 are supported by said rods 18 spaced apart by washers or hubs 19 and near the upper and 25 lower ends of said levers in the rear sides thereof are formed notches 20. The levers 19 correspond in number to the key levers 9, to which they are connected by means of links. The connecting links are all alike, 30 and one of them is shown in detail in Fig. 10. Said link comprises a central portion 21 to the front and rear ends of which are attached slotted plates or loops 22, adapted to receive the lower ends of the levers 19 35 and the upper ends of the vertical arms of the key levers 9, and to rest within the notches 20 in said levers 19 and within corresponding notches 23 in the key levers. As shown in Fig. 2 the links are properly connected to the key levers at different distances 40 from the ends thereof, as a further compensation for the unequal length of the levers in order to secure uniform "touch" and movement. The upper ends of the levers 19 45 are actuated forward by springs 24 connecting the levers with the rods 17. It is obvious that depression of any key lever extends the corresponding spring 24 and that the key levers will be restored to idle position by said springs after operation. The 50 key levers are guided and restrained against lateral oscillation by a series of teeth or projections 25 extending between said levers from a comb plate 26 which is supported 55 under the horizontal arms of the levers.

Supports for the type-bar frames are removably secured to the upper sides of the side frames 2 near the front edges thereof. These supports are symmetrical and consist 60 of the vertical portions 27 and the inwardly projecting horizontal portions 28. Angular frame parts 29 are hinged to the upper ends of the supports, said frame parts conforming in general shape with the supports to 65 which they are hinged, and are sustained in

such position that their horizontal arms may be raised and lowered as hereinafter described. A plate 30 is rigid or integral with each of the frame pieces 29 and said plates are secured to the frames 31 wherein the type-bars are pivoted. The last named frames consist of upper and lower parts the inner ends of which parts in each frame are fastened together and the said parts extending downward and outward therefrom (see Fig. 7). The rear end of a rest piece 32 is fastened to the inner end of each frame 31, said rest pieces projecting forwardly and obliquely downward and outward, and being strengthened by braces 33 connecting their outer ends with the lower corners of the frames 31. The type-bar frames 31 are detachable from the supporting parts 29, so that an entire type-bar frame including all the type-bars thereon may be conveniently taken off the machine for repairing or other desired purposes.

The spindles 34 of the type-bars 35 have bearings in the upper and lower parts of the frame 31. The upper ends of the spindles are threaded (Fig. 12) and receive the interlocking nuts 36 after removal of which the type-bars may be taken out. The several type-bars 35 are rigid on their respective spindles and are preferably formed with hubs 36^a whereby they will be more securely held. The type-bars 35 project forward in substantially horizontal position graduating serially downward and outward on the under sides of the frames 31, as required by the shape of said frames. The type-bars are of the same general shape and are of graduated lengths, and their spindles are arranged at proper inclinations so that when operated they will strike at the same point on the platen. The forward ends of the type-bars bend upward as indicated at 37, one in front of the other so that any one may move without contact with any others. On the parts 37 of the type-bars the type-heads 38 are secured facing inward, each type head having a groove in its outer side whereby it is fastened onto the type bar and having three characters 39 engraved in a row on its inner face (Figs. 3 and 7). The middle character will strike the platen upon operation of the typewriter keys except when the type are moved by the shifting mechanism to cause the upper or lower characters to print. The rear ends of the several type-bars have lateral projections 40 to which are connected the front ends of links 41 leading from levers 19 and connected therewith by slotted plates or loops 42 resting in the notches 20. In this way 45 the several keys are connected with their respective type-bars, all of the connections being illustrated diagrammatically in Fig. 10. Inasmuch as the levers 19 are restored immediately to idle position after the operated 50 55 60 65 70 75 80 85 90 95 100 105 110 115 120 125 130

keys are released, and as the idle position of the type-bars is downward and outward from the printing point, said type-bars will automatically swing back to their idle position after release of the keys.

5 Two standards 43 are secured on the base of the machine and the upper ends of said standards support a track member 44 which has longitudinal grooves 45 in its upper 10 and lower edges. A channel movable member 46 incloses the track member 44 and is provided with longitudinal grooves 47 matching the grooves 45, and within the 15 passages formed by said grooves a number of balls 48 are located to facilitate lateral movement of the platen, and carriage, which are supported by the said member 46. A plate 49 is attached to each end of the 20 part 46 and in said plates the platen shaft 50 is journaled, said shaft carrying the platen 51 which may be of any known or preferred construction. Knobs 52 are attached to the ends of the shaft 50, to be engaged for manual rotation of the platen for 25 line spacing or other purposes, and also afford means to restrain or to move the platen laterally. The rear side of the part 46 carries a rack 53 with which meshes a pinion 54 attached to the forward end of a shaft 30 55. The rear end of the shaft 55 is in an adjustable bearing formed with a supporting part 56 and two screws 57 operating in lateral holes, acting as pivots for the shaft and capable of adjustment to tighten or 35 loosen the shaft therein. The front end of the shaft 55 is mounted in a bearing 58 supported by two arms 59 which are attached to a rock shaft 60, by rocking which the pinion 54 may be lowered out of mesh with 40 the rack 53 and thereby permit unrestrained lateral movement of the platen. The pinion is upheld in mesh with the rack by a spring 61 connecting the upper end of a lever 62 rigid on the rock shaft 60 with a stationary 45 part of the frame. On the rear end of the shaft 55 an escapement wheel 63 is attached, said wheel having a number of teeth or projections 64, shaped substantially as illustrated in Figs. 13, 15 and 17. A rock shaft 50 55 is supported by the frames of the machine below the wheel 63 and has an arm 66 rigid therewith adjacent to the said wheel. An escapement part 67 having a notch 68 in its upper end is separably attached to said arm 66. The peculiar shape 60 65 of the teeth 64 on the wheel and of the notch permits the wheel and shaft 55 to rotate step by step one tooth at a time when the shaft 65 is rocked to oscillate the part 67. This rotating of the shaft 55 permits the platen to be moved step by step leftward as required for letter spacing. To move the platen in this manner a motor 69 of known construction and connection is utilized, said 65 motor being supported on a bracket 70 se-

cured to the track 44. Behind each group of levers 19 a rod 71 is supported by arms 72 attached to the rock shaft 65. From the arrangements of these parts it is obvious that when any of the typewriter keys is depressed the shaft 65 will be rocked and the escapement device operated, so that the platen may be moved one space leftward. The arrangement of the parts comprising the escapement relative to the levers 19 and intermediate parts is such that the platen will be moved only after the type has struck and rebounded so that the printing will be clear and distinct and not blurred or marred as would be the case were the platen to move with the type held against the ribbon.

To operate the escapement and permit the platen to move for word spacing and the like, special mechanism is provided. In 85 front of the keys 3 a space bar 73 is carried on two stems 74 which operate within guides 75 and project below the base (Fig. 1) where they are pivoted to levers 76 attached to a shaft 77. A link 78 is connected 90 to an arm 79 on the shaft 77 and leads to a second link 80 to which it is connected by pin-and-slot connection 81 so that depression of the spacing bar will cause both links to be moved backward, but permitting 95 the link 80 to be moved independently of the spacing bar. The link 80 connects to an arm 82 on a rock shaft 83 at the rear end of the machine. A link 84 connects an arm 85 attached to the rock shaft 83 with an arm 86 rigid on the rock shaft 65, whereby the escapement is operated. From the foregoing it is obvious that operation of the spacing key will cause the escapement controlling the platen to operate and thereby permit the platen to be moved step by step laterally. The plates 49 which carry the platen support a bar 87 which has a series of holes 88 adapted to receive the 100 bearing pins 89 which are removable. Bearings 90 are rigid with the track 44 and a rod or shaft 91 is mounted therein. An arm 92 is mounted on the shaft 91 and is actuated forward against the bar 88 by a spring 93 encircling the shaft. Said arm 105 115 has a projection extending under the bar 87 against which one of the pins 89 will strike and thereby stop the platen when the latter has moved the required distance. These pins may be adjusted to limit right 120 and left movement of the platen and, by proper adjustment, will stop the platen at any desired positions.

Near one end of the shaft 65 (Figs. 5, 15 and 16) is a lever 71^a pivotally supported by 125 the frame of the machine, and adjustably sustained by a screw 71^b in a bracket 71^c. A spring 72^a connects said lever with an arm 72^b attached to the shaft 65, which 130 controls the escapement. The arm 72^b is

between two screws 72^c adjustable in the arms of a bracket 72^d. By adjusting the screws 72^c the scope of swing of the levers 72 and the rods 71 can be regulated, and the tension exerted by the spring 72^a can be increased or reduced by means of the screw 71^b. Said spring operates the escapement members supported by the shaft 65 back to idle position after their operation by the

10 keys.

Near one side of the machine a tabulating key is located, which key is operable to release the escapement from the platen carriage and thereby permit the platen to shift at a single movement any desired distance leftward. Said key comprises a rod 94 (Figs. 2 and 4) supported at its front end in a bearing 95 attached to the frame 2, and connected at its rear end to the lower 20 end of the lever 62 attached to the rock shaft 60. A spring 96 encircles said rod between its head and the bearing 95 and assists in actuating the rod forward and, through the lever 62, in holding the pinion 54 in mesh with the rack 53. A slidable collar 97 is on the end of the rod 94 and bears against the lever 62. A spring 98 encircles the rod 94 in front of the collar 97 and behind another collar, and thereby 25 makes the connection between the rod 94 and the lever 62 yielding but of sufficient tension that when the rod is pushed rearward it will oscillate the lever and thereby rock the shaft 60 and so disconnect the pinion 54 from the rack 53. Thereupon the platen will be drawn leftward and to prevent too rapid movement and sudden stops a brake device is employed to restrain the platen so that it will move quietly and easily 30 until stopped by the pin 89 striking the arm 92. This brake device consists of a lever 98 pivoted to one of the arms 59 and provided with friction part or brake shoe 99 on its upper end adjacent to the bar 87 in 35 the platen frame. An arm 100 on said lever extends over the shaft 60 so that when the arms 59 are lowered said arm 100 will engage against the said shaft 60 and thereby force the part 99 against the bar 87. 40 The frictional contact of the part 99 and the bar 87 will cause the platen to move slowly to position and prevent any sudden jerks or stops. A screw 101 operates through the arm 100 against the shaft 60 and affords 45 means for adjusting the brake to conform to different degrees of pressure as required.

Below the bar 87 a cam bar or shaft 102 is mounted in bearings in the platen end plates 49. The rear side of this bar 102 is a plane (Fig. 20). A lever 103 is mounted on the shaft 91 and has its upper end close against the bar 102 and its lower end extends over one of the arms 59 by which the bearing for the shaft 55 is supported. Rotation of the bar 102 operates the lever 103

and pushes down the arms 59 and thereby disconnects the pinion 54 from the rack 53 and permits the platen to move freely in either direction. A lever 104 is secured to each end of the bar 102 and affords means for manual engagement to turn the bar 102 and thereby operate the lever 103. Such operation permits the platen to be moved manually in either direction and to any desired position in which it may be stopped by releasing the lever 104, whereupon the spring 93 will restore the lever to idle position and permit the escapement again to couple up.

Near the side of the machine the ribbon spools 105 are mounted on vertical shafts 106, the upper ends of which are journaled in bearings in the horizontal parts 28 of the supports for the type-bar frames, and the lower ends project through, and have bearings in, the base 1 (Fig. 1). Slots 107 for said shafts 106 are formed in the horizontal parts of the parts 29 so that the latter may be moved vertically without interference with the shafts. The ribbon 108 winds on the spools and extends across the machine in front of the platen just below the printing line. The lower end of each shaft 106 has a worm wheel 109 attached thereon whereby said shafts will be rotated and the ribbon 90 wound from one spool to the other as desired. A worm 110, of known construction and arrangement, is supported in position to operate the shafts 106. At the middle of the shaft 110 is a toothed wheel 111. The link 80 has a forward projection 112 having teeth engaging with the wheel 111 so that each backward movement of the link will rotate the shaft 110 slightly and thereby the ribbon spool shafts 106 causing the ribbon 105 to wind from one spool to the other. The link 80 is guided by a member 113 attached to the base and having a slot 114 wherein the link moves (Figs. 1 and 25). It is obvious from the foregoing that operation of the spacing bar 73 in addition to causing the platen to travel laterally, will also wind the ribbon from one spool to the other, and it is obvious also that operation of any of the typewriting keys will produce the same result by rocking the shaft 65 and moving the connections leading therefrom to the link 80.

Two arms 115 are suspended from the shaft 91, and said arms are of substantially arcuate shape and extend forward under the platen (Figs. 1 and 13). On the forward ends of these arms a ribbon-guide frame 116 (Figs. 2 and 26) is attached, said frame being in front of the lower part of the platen below the printing line. An upright part 117 having a forwardly extending hook 118 is at each end of the frame, there being a passage or slot 119 separating said upright parts from the frames. The ribbon passes across in front of the platen (Fig. 2) in 130

front of the upright parts 117 under the hooks 118 through the passages or slots 119 and behind the frame 116. In this way the ribbon in idle position is held below the printing line so that the last line of any record will be visible throughout its entire length without rotation of the platen. Obviously, however, the ribbon must be raised each time before the striking of the type to record, and this is automatically accomplished when the typewriter keys are operated. The arms 115 are connected and braced by a rod 120 (Fig. 13) from which a link 121 leads to a lever 122 which is pivotally supported at its lower end at 123. The upper end of said lever 122 is connected to an arm 124 rigid on the rock-shaft 65, by a link 125 so that, when said shaft is rocked by the typewriter key connections, the arms 115 through the medium of the connections just described leading to said shaft, will be raised the required distance to position the ribbon over the printing line to receive the impact of the type. The parts are arranged so that the ribbon will be so positioned before the type strikes, and will be held until the key is released, and the train of connections between the key and its type-bar have started back to idle position. As stated heretofore in describing the type-bars and their frames and supports, it is necessary to move the type to cause the upper and lower characters to print. The plate 5 and the adjacent bearing block 7 (Figs. 28 and 32) support a pivot pin 126 on which is mounted an angular key lever 127, one arm of which extends horizontally forward and is provided with a key 128 arranged at the end of one of the rows of keys 3, and the other arm of which extends downward from the pivot. A lever 129, comprising a vertical part and a horizontal part extending rearwardly from the vertical part midway of the ends thereof, and having a pin 130 at its upper end projecting into a slot 131 in the plate 5, and a pin 132 at its lower end projecting into a slot 133 in said plate, is pivoted to the lower arm of the angular key lever 127 by means of the pin 132 at the lower end of said lever 129. The idle position of the lever 129 is that in which the pins 130 and 132 thereon are in the front ends of their respective slots in the plate 5, and in which the rear arm of said lever is horizontal. A spring 134 is connected to the vertical part of said lever 129 midway of its ends and to a forwardly projecting arm 135 on the plate 5, and serves to hold said lever in idle position and to restore it to such position after operation, all of which will be understood by reference to Figs. 28 and 29. Depression of the lever 127 will raise the rear end of the lever 129, the pin 130 on said lever 129 acting as a pivot therefor, and the pin 132 acting to stop the lever when said

pin reaches the end of the slot 133. A link 136 (Fig. 1) connects the rear end of the lever with one of two arms 137 attached to opposite ends of a transverse shaft 138 supported just above the base of the machine. To each of said arms 137 a vertical link 139 is connected, and the upper ends of said links connect to arms 140 attached to rods or shafts 141 journaled in bearings 142. On the opposite ends of each of said shafts 141 an arm 143 is attached, and said arms are connected to the adjacent pivoted type-bar supports 29 by links 144. From the foregoing it is obvious that depression of the key lever 127 will raise the two groups of type-bars, such movement being limited by the pin 132 in the slot 133. This movement is just sufficient to position the type-bars so that when the typewriter keys are operated the characters 39 which are lowest on the type heads will strike the printing point and record. Upon release of the lever 127 the parts are restored to idle position by the spring 134.

To lower the type as required to print the uppermost characters on the type heads a special key lever 145 is pivoted to the plate 5, and provided with a key 146 also at the end of one of the rows of keys 3. Said lever is pivoted at 147 and has a downwardly projecting arm 148 which is connected to the pin 130 on the lever 129. A slot 149 in said lever 145 receives the pivot pin 126 and permits operation of said lever 145. Depression of the lever 145 oscillates the lever 129 on the pin 132 as a pivot and lowers the rear end of said lever which, through the connections described in connection with the lever 127, lowers the type-bar supports 29, to position the uppermost characters on the type heads for printing. The parts are stopped at the required position by the pin 130 reaching the end of the slot 131. Upon release of the lever 145 the parts are restored to idle position by the spring 134 as in the case of the lever 127.

The manually operable mechanism for moving the platen, and other mechanism cooperating with the platen for adjusting the same, are supported by the plates 49. At the right of the machine relative to the operator, is an angular lever 150 having the end of one of its arms pivoted to the bar 102 and the other arm projecting vertically and provided with a hand-hold 151. An arcuate slot 152 in said lever receives the platen shaft 50 (Fig. 13), and permits oscillation of the lever without obstruction from the shaft. Said lever is sustained by a spring 153. A pin 154 on the lever 150 projects behind the lever 104 so that when the lever 150 is lowered the lever 104 will be operated, which results in release of the escapement from the platen by means of the lever 103 controlled by the bar 102 to which

said lever 104 is attached. It is obvious, therefore, that by operating the lever 150 the platen may be guided manually in either direction and to any desired position. At each end of the platen shaft 50 a ratchet wheel 155 is attached, the teeth on the said wheels being arranged suitable for line "single spacing". The lever 150 carries a T-shaped pawl 156 the lower end of which is actuated forwardly toward the ratchet wheel 155 by a spring 157. The adjacent plate 49 supports a member 158 which has an arm 159 projecting over the top of the pawl 156. A sleeve 160 is slidably mounted on the arm 159 and in the under side of said sleeve a notch 161 is formed. (Fig. 14.) In idle position the end of the front arm on the pawl 156 engages against the sleeve within the notch and in such position the lower end of the pawl is held away from the ratchet wheel 155 so that the platen may be rotated freely in either direction. When the lever 151 is engaged and lowered the pawl 156 engages the wheel 155 and rotates the platen forward two teeth or spaces, and thereby adjusts the paper for "double space" printing. The lever 151 is intended to be engaged after each line of printing to move the platen laterally for the next line, and the rotation of the platen for line spacing is automatically accomplished. If the sleeve 160 be moved endwise the pawl 156 will be held farther back and will engage one tooth lower on the ratchet wheel 155 and, upon operation of the lever 151 will rotate the platen one tooth or space, and thereby adjust the paper for "single space" printing.

162 indicates a feed roller operating, in connection with the platen, to assist in inserting and moving the paper in line spacing. This roller is supported by two levers 163, pivoted to the frames 49, and actuated by springs 164 to hold the roller against the platen. Oscillation of the levers 163 in opposition to their springs 164 will move the roller 162 away from the platen and leave the paper free for manual adjustment. For this purpose levers 165 are attached to a shaft 166 supported by the plates 49 and bear against inclined surfaces of the levers 163, so that operation of said levers 165 will move both of said levers 163 and thereby the roller 162. In addition to the pawls 156 whereby the platen is rotated as before described, a pawl 167 is sometimes arranged to operate upon each of the ratchet wheels 155 and whenever it is desired to rotate the platen to move the paper backward said pawls must be disengaged from the ratchet wheels. Each of said pawls has a pin 168 projecting through a slot 169 in the adjacent plate 49, said pins also projecting over the ends of the levers 165 whereby backward movement of the levers will raise the

pawls and thereby free the platen for rotation in either direction.

In Figs. 1, 2 and 32, I have shown the keys and key levers 170 of an adding or computing machine adapted to be built in combination with the typewriter into an integral machine. These keys are disposed in rows behind the typewriter keys 3, and their levers are arranged in a single group between the two groups of typewriter key levers 9. Said key levers 170 project rearward into the lower portion of the large central space around which the typewriter mechanism is built as described, and wherein a portion of the adding machine mechanism 171 is shown. The typewriter keys are operable independently of the keys 170 to perform all the usual functions of the typewriter and the special functions herein described. Further illustration of the adding machine mechanism is believed to be unnecessary in this application.

I am aware that there may be variations and alterations in the arrangement and combination of the various parts and features described, and in the manner of their coöperation, without in the least departing from the spirit and scope of my invention. In view of such possible variation and alteration I do not restrict myself to identical features of arrangement nor combination of parts, but

What I claim and desire to secure by Letters Patent is:

1. In a typewriting machine, a support rigidly fastened near one side of the machine and another support rigidly fastened near the opposite side of the machine, a group of key levers pivoted in each support, a frame near each side of the machine rearward from said supports, a series of levers in said frames, a frame near each side of the machine adjacent to the platen, a series of type-bars pivoted in each of said last-named frames, connections between the type-bars and the levers in the first-named frames, connections between the key levers and said levers in said frames, and a platen arranged to hold paper to receive records produced by the type-bars, substantially as specified.

2. In a typewriting machine, a support removably located near each side of the machine, a group of key levers of different lengths pivoted at different heights in said supports, a frame removably located near each side of the machine, a series of type-bars of graduated lengths pivoted in each of said frames, connections between the key levers and the type-bars, a platen arranged to hold paper, and means for holding the type-bars in different positions for different records, substantially as specified.

3. In a typewriting machine, a support removably located near each side of the machine, a group of key levers pivoted in each

support, a frame removably located near each side of the machine, a series of type-bars of graduated lengths pivoted in each of said frames, connections between the key levers and the type-bars, a platen arranged to hold paper, and shift key mechanism connected with said frames whereby said frames may be moved to different positions for different records, substantially as specified.

4. In a typewriting machine, a support removably located near each side of the machine, a group of key levers pivoted in each of said supports, a frame removably located near each side of the machine, a series of type-bars of graduated lengths pivoted in each of said frames, connections between the key levers and the type-bars, springs effective to restore the key levers to idle position connected to said connections, a platen arranged to hold paper, and shift mechanism operable to move and hold the type-bars into different positions for different records, substantially as specified.

5. In a typewriting machine, a support located near each side of the machine, a group of key-levers pivoted in each of said supports, a movable frame located near each side of the machine, a series of type-bars pivoted in each of said frames, connections between the key-levers and the type-bars, a platen arranged to hold paper, shift devices for moving the type-bars to different positions for different records, and springs connected with said shift devices and acting to hold said movable frames in normal position, substantially as specified.

6. In a typewriting machine, a support located near each side of the machine, a group of key-levers pivoted in each of said supports, a frame removably located near each side of the machine, a series of type-bars pivoted in each of said frames, connections between the key-levers and said type-bars, a shift key operable to move said frames and type-bars in one direction from their normal position, a spring operable effectively to return said frames and type-bars to normal position after being moved by said shift key, another shift key operable to move said frames and type-bars in the other direction from their normal position, and a spring operable effectively to return said frames and type-bars to normal position after being moved by said last-named shift key, substantially as specified.

7. In a typewriting machine, the combination with the type-bar supports, type-bars mounted in said supports, and levers for actuating said type-bars, of links connected to said supports, levers connected to said links, a link extending downwardly from each of said levers, a shaft, arms on said shaft connected to each of said last-named links, a lever connected to said shaft, and two keys operable to actuate said last-

named lever in opposite directions whereby operation of one of said keys will raise said type-bar supports and type-bars and the operation of the other will lower said supports and bars, substantially as specified.

8. In a typewriting machine, a frame removably mounted near each side of the machine, a group of type-bars carried by each frame, a group of key-levers pivoted near each side of the machine and each group being removable as a group, finger pieces rigid with said pivoted key-levers, connections leading from the key-levers of one group to the type-bars of the corresponding group respectively, whereby the type-bars will be operated when the key-levers are depressed as required to print, a platen arranged to feed paper to said type-bars, and mechanism operable to shift both groups of type-bars to different printing positions, substantially as specified.

9. In a typewriting machine a movable frame mounted near each side of the machine, a group of type-bars carried by each frame, a group of key-levers pivoted near each side of the machine and each group being removable as a group, finger pieces on said pivoted key-levers, connections from the key-levers of one group to the type-bars of the corresponding group, respectively, whereby the type-bars will be operated when the key-levers are depressed, shift keys, and mechanism operated by said shift keys to shift both groups of type-bars to different printing positions, substantially as specified.

10. In a typewriting machine, a separate support removably attached near each side of the machine, a group of key levers pivoted in each support and being removable therewith as a group, a finger button rigid with each pivoted key-lever, a frame pivoted near each side of the machine, a series of type-bars of graduated lengths pivoted in each frame and each series of type-bars being removable as a group, connections whereby the key-levers of each group will operate the corresponding type-bars, respectively, and a platen arranged to hold paper for the records, substantially as specified.

11. In a typewriting machine, a separate support removably attached near each side of the machine, a group of key-levers pivoted in each support and being removable therewith as a group, a finger button rigid with each pivoted key-lever, a frame pivoted near each side of the machine, a series of type-bars of graduated lengths pivoted in each frame and each series of type-bars being removable as a group, connections whereby the key-levers of each group will operate the corresponding type-bars, respectively, a platen arranged to hold paper for the records, and means for moving said

pivoted frames and thereby the type-bars to different printing positions, substantially as specified.

key, another shift key operable to move said frames and type-bars in the other direction 60 from their normal position, and a spring effective to return said frames and type-bars to normal position after being moved by said last-named shift key, substantially as specified.

12. In a typewriting machine, a support 5 removably located near each side of the machine, a group of key-levers pivoted in each support, a frame removably located near each side of the machine, a series of type-bars of graduated lengths pivoted in each of said frames, connections between the key-levers and the type-bars, a platen arranged to hold paper, and shift key mechanism connected with said frames whereby said frames and said type-bars may be 10 moved to different positions for different records, substantially as specified.

13. In a typewriting machine, a support 20 removably located near each side of the machine, a group of key-levers pivoted in each of said supports, a frame removably located near each side of the machine, a series of type-bars of graduated lengths pivoted in each of said frames, connections between the key-levers and the type-bars, 25 springs effective to restore the key-levers and type-bars to idle position after operation, a platen arranged to hold paper, shift mechanism operable to move and hold the type-bars into different positions for different records, substantially as specified.

14. In a typewriting machine, a support located near each side of the machine, a group of key-levers pivoted in each of said supports, a movable frame located near each 35 side of the machine, a series of type-bars pivoted in each of said frames, connections between the key-levers and the type-bars, a platen arranged to hold paper, shift devices for moving the type-bars to different positions 40 for different records, and springs operable to restore said shift devices and said movable frames to normal position after each operation thereof, substantially as specified.

45 15. In a typewriting machine, a support located near each side of the machine, a group of key-levers pivoted in each of said supports, a frame removably located near each side of the machine, a series of type-bars pivoted on each of said frames, connections between the key-levers and the type-bars, a platen arranged to feed paper to said type-bars, a shift key operable to move said frames and type-bars in one direction 50 from their normal position for printing on said paper, a spring effective to return said frames and type-bars to normal position after being moved by said shift

key, another shift key operable to move said frames and type-bars in the other direction 60 from their normal position, and a spring effective to return said frames and type-bars to normal position after being moved by said last-named shift key, substantially as specified.

16. In a typewriting machine, the combination with the type-bar supports, of links connected to said supports, levers connected to said links, a link extending downwardly from each of said levers, a shaft, arms on 70 said shaft connected to each of said last-named links, a lever connected to said shaft, and two keys operable to actuate said last-named lever in opposite directions whereby operation of one of said keys will raise said 75 type-bar supports and the operation of the other will lower said supports, substantially as specified.

17. In a typewriting machine, a platen arranged to hold paper, a pivoted frame removably supported near each side of the machine, a group of type-bars in each frame operable to record on the platen when in three different positions and being removable as groups with said frames, means automatically holding said type-bars in one of said positions, levers for moving said type-bars to the other two positions, removable supports and key mechanism mounted in said supports and being removable therewith as groups and being operable to cause the type-bars to record on paper on said platen in any position on said type-bars, substantially as specified.

18. In a typewriting machine, a series of 95 type-bars arranged in separate groups, two removable supports, a group of keys arranged in each of said supports, connections whereby said keys will operate said type-bars, shift keys mounted in one of said removable supports and being removable with the group of keys aforesaid, a platen arranged to feed paper to said type-bars, and connections from said shift keys for changing the relative position of said type-bars and said platen, substantially as specified.

In testimony whereof, I hereto affix my signature to this specification this 29th day of August, 1906, in the presence of two witnesses.

WILLIAM H. CLAYTON. [L. S.]
